UNITED STATES PATENT OFFICE.

JAMES DWYER AND JOHN H. LANE, OF DETROIT, MICHIGAN, ASSIGNORS TO
THE PENINSULAR STOVE COMPANY, OF SAME PLACE.

DESIGN FOR A COMBUSTION-CHAMBER FOR STOVES.

SPECIFICATION forming part of Design No. 31,648, dated October 10, 1899.

Application filed June 24, 1899. Serial No. 721,785. Term of patent 14 years.

To all whom it may concern:

Be it known that we, JAMES DWYER and JOHN H. LANE, citizens of the United States, residing at Detroit, in the county of Wayne and State of Michigan, have invented and produced a new and original Design for a Combustion-Chamber for Stoves, of which the following is a specification, reference being had therein to the accompanying drawings.

Figure 1 is a perspective view of a combustion-chamber, showing our new design; and Fig. 2 is a side elevation thereof.

As shown in the drawings, the leading or material feature of our design consists in the configuration thereof, which comprises an essentially dome-shaped body with a projection at one side of the top.

A is the body of the combustion-chamber, which is essentially dome-shaped, as shown.

Projecting from the rear face, near the top, is the projection B, as shown. The dome-shaped body comprises a plurality of upright columns or posts *a*, having connecting arched tops *b*. Between said columns and arches are the convex panels *c* and *d* at the front and sides, respectively, and the convex panel *e* at the top. These panels *c*, *d*, and *e* are formed of ornamental open-work.

What we claim is—

The design for the combustion-chamber of a stove as herein shown and described.

In testimony whereof we affix our signatures in presence of two witnesses.

JAMES DWYER.
JOHN H. LANE.
